UNITED STATES PATENT OFFICE

2,436,537

MICROMETER CALIPER

Robert A. Wilkinson, North Hollywood, Calif.

Application November 14, 1945, Serial No. 628,397

2 Claims. (Cl. 33—148)

1
The invention relates to micrometer calipers, for the use of machinists and draftsmen, having for an object to provide an improved device of this description adapted to give simultaneous readings in thousandths of an inch as well as in inches and thus save time. Another object is to provide such a device adapted for use to give readings in inches only. Other objects and advantages will appear hereinafter or will be obvious.

The invention consists in the novel construction and combinations of parts as hereinafter set forth in the claims.

In the accompanying drawings,

Figure 1 is a front view of the calipers, designed for inside readings.

Figure 2 is an edge view of the same.

Figure 3 is a view similar to Fig. 1, of the calipers as designed for outside readings, the dials being removed.

Figure 4 is a detail side view of one leg of the calipers.

Figure 4a is a detail edge view of the same.

Figure 5 is a detail edge view of the other leg.

Figure 5a is a detail side view of the same.

Figure 6 is a detail side view of the pivot pin.

Figure 6a is a detail end view of the same.

Figure 7 is a detail fragmentary side view of the dial case, partly in section, showing the thousandths dial and the manipulable means for disengaging the pinion.

Figure 8 is a detail side view of said manipulable means on a larger scale.

Figure 9 is a detail fragmentary face view of the inches dial, showing the thousandths dial and its brake springs.

In these drawings, the numeral 1 designates the legs of the calipers, having a pivotal connection, one of said legs having two parallel spaced hollow cylindrical hub projections 3, within which fits a single hollow cylindrical hub projection 4 of the other leg, a pivot pin 5 being fast to the projection 4, within the perforation thereof to move with said leg and engaging the perforations of the projections 3, said pin having a central longitudinal axial perforation 6, within which is secured a drive shaft 7 to move with said pin, as the calipers are opened or closed in taking readings.

A circular case 8 is spaced laterally of said legs, with its center located centrally of said legs, the outer face of said case forming the inches dial 9. An anchor 10 for said case is secured to one of said legs to hold the case stationary with respect to said leg.

2
The drive shaft 7 is provided with a spur gear wheel 11, meshing with a pinion 12, the shaft of which pinion has an inches hand 13 fast thereto. A thousandths dial 15 is located within the inches dial and is separate therefrom for separate manipulation purposes as will be explained. A second pinion 16 has a gear train connection 17 with the shaft of said first named pinion, a thousandths hand 18 being secured to the shaft of said second pinion.

Manipulable means are provided for shifting said second pinion 16 out of and into mesh with said gear train, during such manipulation and thereafter, said means comprising a shifting lever 19, fulcrumed at 20, and engaging at its forked upper end with a throwout collar 22, to accomplish the shifting, a push and pull pin 23 having bearings in a lateral wall of said case and being provided with spaced seats 24 within one or the other of which a spring-pressed ball 25 of the case engages to hold the lever as shifted with said pinion in mesh with the gear train or released therefrom.

Simultaneous readings may be taken in inches and thousandths of an inch, or other fractions of an inch than thousandths; or readings may be taken in inches only upon shifting said second pinion out of mesh with said gear train.

The thousandths dial has an arcuate portion 30 thereof projecting without the circumferential edge wall of said case, for convenient use in manipulation, after the said second pinion has been shifted out of mesh with said gear train, in setting the calipers prior to use, in taking inch dimensions only, as aforesaid, or in resetting the hands to zero, the latter being prior to such shifting. Hair springs (not shown) are used to take up slack in the gears and to take up slack in the hand of the inches dial, so that there shall be no lost motion. Brake springs 26 are provided for the thousandths dial so that it shall not work too freely. This thousandths dial is secured by suitable means (not shown) to the inches dial face plate so that it shall be capable of being rotated.

The drive shaft 7 being secured centrally of the pivot pin 5 as aforesaid provides for more accurate readings, inasmuch as it is of small cross sectional area and the movement of rotation 50 thereof in opening and closing the calipers is comparatively slight, thereby reducing liability of error. This location also does away with need for more elaborate or complicated means for communicating the movement of the legs of the calipers in taking readings to the dial hand or

hands, and also provides for location of the circular dial case centrally with respect to said legs for a balanced construction. The pivotal or hub construction aforesaid is designed to reduce lost motion to a minimum.

I claim:

1. A micrometer calipers, having two legs provided with a pivot pin connection, said pin being fast to one of said legs to move therewith and having a longitudinal axial perforation, a drive shaft secured within said perforation to move with said pin, an inches dial, a gear upon said drive shaft, a pinion meshing with said gear, an inches hand upon the shaft of said pinion, a thousandths dial located within said inches dial and separate therefrom, a second pinion having a gear train connection with the shaft of said first named pinion, a thousandths hand upon the shaft of said second pinion, said thousandths dial having an arcuate portion thereof projecting without the circumference of said inches dial for manipulation purposes, manipulable means for shifting said second pinion out of mesh with said gear train during such manipulation, said inches dial being spaced laterally of said legs, and an anchor for said inches dial fast to one of said legs.

2. A micrometer calipers, having two legs provided with a pivot pin connection, said pin being fast to one of said legs to move therewith and having a longitudinal axial perforation, a drive shaft secured within said perforation to move with said pin, an inches dial, a gear upon said

drive shaft, a pinion meshing with said gear, an inches hand upon the shaft of said pinion, a thousandths dial located within said inches dial and separate therefrom, a second pinion having a gear train connection with the shaft of said first named pinion, a thousandths hand upon the shaft of said second pinion, said thousandths dial having an arcuate portion thereof projecting without the circumference of said inches dial for manipulation purposes, manipulable means for shifting said second pinion out of mesh with said gear train during such manipulation, a circular case the outer face of which forms said inches dial, said case being spaced laterally of said legs, said gear, said gear train, both pinions, and said manipulable means being located within said case, and an anchor for said case fast to one of said legs.

ROBERT A. WILKINSON.
